(57) CLAIM

The ornamental design for a brush handle, as shown and described.

DESCRIPTION

FIG. 1 is a front elevational view of a brush handle, showing my new design with environmental context;

FIG. 2 is a front elevational view thereof (and also a mirror image of the rear elevational view);

FIG. 3 is a side elevational view thereof (and also a minor image of the opposite side); and

FIG. 4 is a bottom view thereof; and,

FIG. 5 is front elevational view thereof showing an element of the handle in an alternate position.

The broken lines showing a brush head illustrate environmental structure that forms no part of the claimed design. FIGS. 2-5 are shown on an enlarged scale.
